UNITED STATES PATENT OFFICE.

PAUL THAMM, OF NEW YORK, N. Y., ASSIGNOR, BY MESNE ASSIGNMENTS, TO C. BLAIR
WOODROW.

OIL FILLER AND BREATHER.

Refiled for abandoned application Serial No. 384,948, filed May 28, 1920. This application filed December 27, 1922. Serial No. 609,347.

To all whom it may concern:

Be it known that I, PAUL THAMM, residing at New York city, in the county of New York and State of New York, a citizen 5 of the United States, have invented certain new and useful Improvements in Oil Fillers and Breathers; and I do hereby declare the following to be a full, clear, and exact 10 description of the invention, such as will enable others skilled in the art to which it pertains to make and use the same.

My present invention relates to a crankcase, the invention being more particularly related to a combined oil-filler and 15 "breather" for a crankcase.

The principal object of my invention is the provision in a crankcase of a projecting oil-filler chute having a hinged closure which also serves as a "breather," the same 20 including a spring pressed diaphragm which is adapted to respond to the variation of pressure within the crankcase, due to the reciprocating motion of the piston.

The present application is a substitute for 25 my application filed May 28, 1920, Serial No. 384,948.

My invention consists in the several features and in the construction, combination and arrangement of such features as more 30 fully hereinafter described and claimed.

For full understanding of my invention, reference is to be had to the following description and accompanying drawing, in which I illustrate the preferred embodiment 35 of the invention as reduced to practice, and in which:—

Fig. 1 is a view in front elevation of a fragment of the crankcase, showing my improved oil-filler chute and "breather" attached thereto.

Fig. 2 is a central vertical cross-section through the parts shown in Fig. 1.

Referring in detail to the parts shown in the drawing, the numeral 3 represents the 45 wall of the crankcase the wall 3 being provided with an opening 4, which is closed by a plate 5, securely bolted at intervals as at 6 to the wall. The plate 5 is provided with an outwardly inclined oil-filler chute 7, substantially cylindrical in form, and which 50 communicates through the opening 4 directly with the interior of the crankcase.

At its outer end the oil-filler chute 7 has a circular opening 8, through which the oil is introduced into the crankcase. 55

The outer end of the oil-filler chute 7, adjacent the plate 5, is provided with an upstanding lug 9 through which is passed the pintle 10, engaged in the knuckles 11, which are cast with the cap or closure plate 60 13, and by means of which the cap or closure plate is hingedly connected with the oil-filler chute so as to fit flat upon the top 14 thereof. The forward end of the cup or closure plate 13 is cast with a projecting lug 65 15, designed to fit flat upon a correspondingly projecting lug 16, cast or formed on the oil-filler chute for a purpose presently to appear.

The cap or closure plate 13, except for 70 the projecting knuckles 11 and the projecting lug 15, is of circular form, as shown, to conform with the form of the oil-filler chute; and it is provided with a central opening 17, adapted to register substantially 75 with the opening 8 of the oil-filler chute. Secured upon the outer face of the cap 13, so as to entirely close the opening 17

therein, is a diaphragm 18, made preferably 80 of leather or other suitable fabricated material adapted to be flexed in response to variations of pressure which occur within the crankcase. 19 represents a disk-shaped spring, which is curved inwardly all around 85 as at 20, adjacent its circumference and rests upon the diaphragm 18, opposite or substantially opposite the opening 17. This member 19, at its central portion 21, is curved outwardly to provide a space 22 for the flexing of the diaphragm in response to pressure. Riveted at 23 to the center of the member 19 is a spring plate 24 which extends outwardly and is bent 90 downwardly at 25 so as to rest flat at 26 upon the diaphragm, and which together 95 with the diaphragm is secured by a rivet 27 to the projecting lug 15.

The spring 24 is bowed outwardly and 100 downwardly at 28 over both the lugs 15 and 16 and terminates in a hook shaped detent 29, adapted to snap under the lug 16 so as to hold the cap or closure 13 tightly upon the end of the oil-filler chute.

When it is desired to introduce oil through

the oil filler chute, it is only necessary to disengage the hook-shaped end 29 of the 5 detent from the lug 16 and to raise the cap or closure into the position illustrated in Fig. 1. When the cap or closure is swung downwardly and secured upon the oil-filler chute, as shown in Fig. 2, the spring-pressed diaphragm serves as a "breather" to take care of variation of pressure within the 10 crankcase and due to the reciprocating motion of the piston. For instance, under the down stroke of a vertically operating piston, the diaphragm will be flexed outwardly in the space provided by the outwardly 15 convexed portion 21 of the disk-shaped element 19; and if the pressure be severe enough, the disk-shaped element, under the yielding of the spring 24, will permit the diaphragm, particularly in the region 20 adjacent the hinged engagement of the cap, to rise from the face of the cap so that the air under pressure may escape from the oil-filler-chute. Under the upstroke of the piston, the diaphragm is flexed inwardly to 25 seal the opening 8; and if the suction produced by the piston is severe enough, the diaphragm will be flexed slightly to permit the entrance of a small amount of outside air between the diaphragm and the 30 cap at the region adjacent the hinge.

I do not wish to be understood as limiting myself to the specific details of construction and arrangement as herein described and illustrated, as it is manifest 35 that variations and modifications may be made in such features or construction and arrangement, in the adaptation of the device to the various conditions of use, without departing from the spirit and scope of 40 my invention and improvements. I, therefore, reserve the right to all such variations and modifications as properly fall within the scope of my invention and the terms of 45 the following claims.

What I claim is:—

1. In an oil-filler and breather cap for filling tubes for a crank case of internal combustion engines, a closure therefor including an annular member hingedly connected to said crank case adjacent the mouth of said tube, a flexible diaphragm secured to the upper face of said annular member and means for resiliently pressing said diaphragm against said annular member and adapted normally to effect an air tight seal between said diaphragm and annular member but to permit flexing of the diaphragm away from said member due to variations of pressure within the crank case.
2. In a combined oil-filler and breather cap for a filling tube for a crank case of an engine, a cap member hinged to said tube adjacent its mouth and formed with a circular opening therein overlying said tube, a flexible diaphragm covering said opening

and resilient means mounted upon said member and engaging said diaphragm to exert a pressure thereon uniformly distributed along the line of engagement between the diaphragm and the edge of the opening in said cap member.

3. In a combined oil-filler and breather cap adapted for attachment to a filling tube of a crank case for an engine, a closure therefor hinged to said tube and having an opening therein, a flexible diaphragm cov-

ering said opening, and a concavo-convex spring attached to said closure, and exerting a pressure in said diaphragm substantially coincident with the opening in said closure for the purpose of keeping said diaphragm pressed against said closure.

4. In a combination with a crank case having an opening, means for closing said opening consisting of a ring-plate hinged to fit flat around said opening, a flexible diaphragm extending over the outer surface of said ring-plate and entirely closing the opening therein, a disk-shaped outwardly curved element bearing on said diaphragm and permitting the flexing thereof, a spring holding said disk-shaped element and secured with said diaphragm to the ring-plate, and means for securing said ring-plate in closed position.

5. In combination with a crank case having an opening and a lug, means for closing said opening consisting of a ring-plate hinged to fit said opening, a flexible diaphragm extending over the outer surface of said ring-plate and entirely covering the opening therein, a disk-shaped outwardly curved element bearing on said diaphragm and permitting the flexing thereof, and a spring holding said disk-shaped element and secured fast with said diaphragm to the ring-plate opposite the hinged engagement thereof, said spring having a hooked extension adapted to snap under said lug for securing said ring-plate in closed position.

6. The combination of an oil-filler chute having an end with an opening, means for closing said opening consisting of a plate hinged to the oil-filler and adapted to fit on said end and having an opening therethrough adapted to register with said oil-filler chute opening, a flexible diaphragm extending over the outer surface of said hinged plate and entirely covering the opening therein, a disk-shaped outwardly convexed element bearing on said diaphragm and permitting the flexing thereof, a spring holding said disk-shaped element and secured together with said diaphragm to said plate, and means for holding said plate tightly on said oil-filler end.

7. The combination of an oil-filler chute having an end with an opening, means for closing said opening consisting of a plate hinged to the oil-filler chute and adapted to

fit on said end and having an opening there-through adapted to register with said oil-filler opening, a flexible diaphragm extending over the outer surface of said hinged plate and entirely closing the opening therein, a disk-shaped outwardly curved element bearing on said diaphragm and permitting the flexing thereof, a spring holding said disk-shaped element and secured together

with said diaphragm to the end of the oil-filler chute at a point opposite the hinged engagement thereof, said spring having a hook-shaped detent extension, and means on the oil-filler chute over which the said detent may engage.

In testimony whereof I have affixed my signature.

PAUL THAMM.
